(57) **CLAIM**

The ornamental design for a “EMI protective spring plate,” as shown and described.

DESCRIPTION

FIG. 1 is a perspective view of an “EMI protective spring plate” showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The EMI protective spring plate of FIGS. 1 and 4–7 is shown broken-away in the views to indicated unclaimed length.
